[57] CLAIM

The ornamental design for the “fishing lure,” as shown and described.

DESCRIPTION

FIG. 1 is an elevational view of a new design for a fishing lure, the opposite view being a mirror image thereof;

FIG. 2 is a top view;

FIG. 3 is an end view, taken from the hook end;

FIG. 4 is an end view, taken from the sinker end;

FIG. 5 is an elevational view of a second embodiment, the opposite being a mirror image thereof;

FIG. 6 is a top view of the embodiment shown in FIG. 5;

FIG. 7 is an end view, taken from the hook end, of the FIG. 5 embodiment;

FIG. 8 is an end view, taken from the sinker end, of the FIG. 5 embodiment;

FIG. 9 is an elevational view of a third embodiment, the opposite view being a mirror image thereof;

FIG. 10 is a top view of the embodiment shown in FIG. 9;

FIG. 11 is an end view, taken from the hook end, of the FIG. 9 embodiment;

FIG. 12 is an end view, taken from the sinker end, of the FIG. 9 embodiment;

FIG. 13 is an elevational view of a fourth embodiment, the opposite view being a mirror image thereof;

FIG. 14 is a top view of the embodiment shown in FIG. 13;

FIG. 15 is an end view, taken from the hook end, of the FIG. 13 embodiment; and,

FIG. 16 is an end view, taken from the sinker end, of the FIG. 13 embodiment.

The portion of the fishing line is shown broken away in the middle in FIGS. 1, 2, 5, 6, 9, 10, 13, and 14 to indicate indeterminate length.
